United States Patent Office

Des. 202,591
Patented Oct. 19, 1965

202,591

BOAT

Eugene C. Lowe, Jr., Hialeah, Fla., assignor to Aztec
Boat Corporation, Hialeah, Fla., a corporation of Florida

Filed May 13, 1964, Ser. No. 79,964

Term of patent 14 years

(Cl. D71—1)

Fig. 3.

Fig. 4.

The side not shown is the same in appearance as that shown in FIGURE 1.

I claim:

The ornamental design for a boat, as shown and described.
